DESIGN FOR A HANDBAG

Louis Carl Levine, New York, N. Y.

Application November 1, 1941, Serial No. 103,984

Term of patent 7 years

To all whom it may concern:

Be it known that I, Louis Carl Levine, a citizen of the United States, residing in New York city, in the county of New York and State of New York, have invented a new, original, and ornamental Design for a Handbag, of which the following is a specification, reference being had to the accompanying drawing, forming part thereof.

Fig. 1 is an elevational front view of a handbag showing my new design;

Fig. 2 is an elevational rear view of the handbag shown in Fig. 1;

Fig. 3 is a slightly enlarged fragmentary perspective view of the top portion of the handbag shown in Figs. 1 and 2 in open position; and

Fig. 4 is a slightly enlarged fragmentary perspective view thereof with the frame in closed and the closure flap in open position.

The characteristic feature of my design resides in the portion shown in full lines on the drawing.

I claim:

The ornamental design for a handbag, substantially as shown and described.

LOUIS CARL LEVINE.
